United States Patent Office.

LUCIUS BRIGGS, OF GROSVENOR DALE, CONNECTICUT, ASSIGNOR TO HIMSELF AND GEORGE BUNTIN, OF SAME PLACE.

Letters Patent No. 82,684, dated October 6, 1868.

IMPROVEMENT IN TEMPLES FOR LOOMS.

The Schedule referred to in these Letters Patent and making part of the same.

TO ALL PERSONS TO WHOM THESE PRESENTS MAY COME:

Be it known that I, Lucius Briggs, of Grosvenor Dale, in the county of Windham, and State of Connecticut, have invented a new and useful Improvement in Roller-Temples for Looms; and I do hereby declare the same to be fully described in the following specification, and represented in the accompanying drawings, of which—

Figure 1 is a top view, and

Figure 2 a longitudinal section of one of my improved temples, the plane of section being along the axis of the centre-pin of the roller.

In such drawings, A denotes the toothed roller; B, the trough; C, the cap; D, the holding-plate; and E, the centre-pin, such being parts of a common roller-temple, usually known as the "Dutcher roller-temple."

The object of my improvement is to enable the rubbing-surfaces of the roller and its centre-pin to be easily oiled, as occasion may require.

For this purpose, I form the centre-pin with a passage, *a*, extending from or near its outer end to or towards the middle of the pin, and opening through one side of the pin, at or near such middle, I extend the head, *b*, of the pin beyond the head or abutment, *c*, of the trough, and I make in the said extension a hole, *d*, to lead down into the passage *a*.

By pouring a small amount of oil into the hole *d*, it will run through the passage *a*, and be discharged out of its end and upon the contiguous bearing-surfaces of the roller and the centre-pin, and thus, at any time, the said surfaces may be lubricated without the oil getting upon the cloth while passing through the temple.

An oil-induct hole might be made through the cap and abutment and the centre-pin, so as to lead into the passage *a* of such pin, but as the centre-pin is screwed into the inner end of the cap, a rotary movement of the pin while screwing it up would be likely to cut off the communication between its oil-passage and the passage of the abutment, therefore I prefer to extend the head of the pin beyond the abutment, so as to enable me to make the induct in the said head in the manner described.

I claim, in a roller-temple, the centre-pin, as extended beyond the trough-head, as set forth, and provided with passages leading into the extension, and through the pin, substantially as and for the purpose specified.

I also claim, in a roller-temple, the centre-pin, as made with an oiling-passage made through it lengthwise, and opening out of the side of the pin.

LUCIUS BRIGGS.
